Patented Feb. 20, 1900.

A. L. MACLACHLAN.

SHAFT TUG.

(Application filed Nov. 15, 1899.)

(No Model.)

UNITED STATES PATENT OFFICE.

ANDREW L. MACLACHLAN, OF MELROSE, MASSACHUSETTS.

SHAFT-TUG.

SPECIFICATION forming part of Letters Patent No. 643,665, dated February 20, 1900.

Application filed November 15, 1899. Serial No. 737,056. (No model.)

To all whom it may concern:

Be it known that I, ANDREW L. MACLACHLAN, a citizen of the United States, residing in Melrose, in the county of Middlesex and State of Massachusetts, have invented new and useful Improvements in Shaft-Tugs, of which the following is a specification.

This invention relates to that class of shaft-tugs in which a number of oval pieces of leather are provided with oval openings and the said oval pieces are pressed together and afterward permanently secured, so that the tug comprises a number of layers. In order to apply buckles to tugs of this description, it is necessary to bore a hole in the tug at the proper end and thrust one of the bars (detached for the purpose) of the frame or loop of the buckle through the hole and then to apply the remainder of the said frame or loop to the bar which lies in the hole. It is obvious that a "whole-loop" buckle—*i. e.*, a buckle having an integral frame—cannot be applied to this style of shaft-tug.

The object of my invention is to construct a shaft-tug of the character described which is capable of receiving a buckle having an integral frame or loop and of having any ordinary buckle applied to or removed from it without destroying or injuring either the buckle or the tug.

The nature of the invention is fully described below and illustrated in the accompanying drawings, in which—

Figure 1 is a perspective view of my improved shaft-tug with the securing or clamping plate removed. Fig. 2 is a similar view of a buckle provided with an integral frame or loop. Fig. 3 is a view of the clamping or securing plate removed. Figs. 4 and 5 represent the bolts before they are placed in position. Fig. 6 is a perspective view of the shaft-tug complete and with the buckle in position. Fig. 7 is a vertical section taken through the buckle and the upper end of the tug. Fig. 8 is a horizontal section taken on line Y, Fig. 7.

Similar letters of reference indicate corresponding parts.

A represents the body of the tug, constructed of numerous layers of leather A'. At the points *a* near the end at which the buckle is to be applied these layers are cut verti-

cally, as shown in Fig. 1, to a depth corresponding to the thickness of the clamping or securing plate below described. Midway 55 between the points *a* a radial transverse cut B is made across the layers and through the body of the tug. A large opening C is cut to receive the looped end *b'* of the tongue *b* of the buckle, said opening being of substantially the shape shown and extending on opposite sides of the cut B. A horizontal bore D is made transversely and horizontally through the layers and extends on opposite sides of the cut B. This bore is of a size to 60 receive the portion *e'* of the frame or loop *e* of the buckle. A pair of smaller bores E are formed upon opposite sides of the cut B for the purpose of receiving the bolts which secure the plate in place. In constructing this 65 portion of the tug the openings C, D, and E may be first made and then the cut B formed across the openings C, D, or the order of the process may be changed as desired.

A metallic plate is formed consisting of the 70 curved end F, provided with the slot F', made longer than it is wide, and the flat sides H, each provided with a central radial recess H' and two perforations H'', the pairs of perforations being opposite each other. 80

To apply the buckle, spread the upper end of the tug forcibly apart sufficiently to allow the bar *e'* to be pushed down within the cut B until it reaches the curved recesses which constitute the bore D. Pass the plate over 85 the tongue *b*, so that said tongue projects through the opening F', and then press it down between the edges *a* with its slots H' over the portion *e'* of the buckle on opposite sides of the tongue. The parts of the tug are 90 then pressed together, if necessary, and bolts K are driven through holes H'' in the plate and the coincident perforations E in the tug, the entering ends of the bolts being then riveted over the edges of the plate. In this position, as will be seen, the bar *e'* of the buckle lies in the bore D and the portion *b'* of the tongue in the recess C, and the buckle is free to swing in either direction. To remove the buckle, the rivets are removed by punching 95 them back with a rivet set and the buckle taken out by spreading the body of the tug.

It is evident that any style of buckle, whether its frame is integral or not, can be ap-

plied to the tug, provided the portion e' is not too large, and should that be the case the bore D can be reamed out or enlarged, as desired.

As this tug is composed of layers or lifts of leather, it is evident that the best and easiest method of producing the opening C is to cut transversely through a given number of layers, the number shown in the drawings being two.

10 It is apparent that in case of breakage another buckle can be substituted with considerable economy of time.

Having thus fully described my invention, what I claim, and desire to secure by Letters 15 Patent, is—

The herein - described improvement in shaft-tugs, comprising the body portion A recessed as described between the points a, the portion of the tug between said points being provided with the cut B, radially-set central 20 opening C and horizontal bore D; and the plate comprising the top portion F provided with the slot F', and the side portions H provided with the recesses H' and perforations H" for the reception of fastening-bolts, substantially as described.

ANDREW L. MACLACHLAN.
